UNITED STATES PATENT OFFICE.

WALTER F. SCHULZ, OF SHARON, PENNSYLVANIA, ASSIGNOR TO TRUSCON STEEL COMPANY, OF YOUNGSTOWN, OHIO, A CORPORATION OF MICHIGAN.

MACHINE FOR STRAIGHTENING WIRE.

Application filed March 31, 1923. Serial No. 628,966.

This invention relates to a machine for straightening wire, which is adapted to operate upon wire of a kinky, wavy or undulatory nature and to entirely remove all 3 kinks or bends therefrom and to deliver the wire perfectly straight and true.

The object of the invention is to provide a machine adapted to accomplish the result above referred to which machine is of relatively simple construction and of relatively small and compact form, requiring a minimum of power for its operation.

The invention consists primarily of a plurality of annular and independently rotatable elements or rings arranged in staggered or offset relation and adapted to engage the wire at spaced points therealong, which elements are bodily revolved about an axis which is substantially co-incident with the path of the wire. The effect of the rolling engagement of these revolving and independently rotatable annular elements upon the wire passing therethrough is to remove all irregularities, such as kinks, or 25 bends therefrom, and to render the wire perfectly straight.

The invention also comprises the various other features and constructions which will be more fully pointed out hereinafter and 30 clearly set forth in the appended claims.

One embodiment of the present invention is illustrated in the accompanying drawings, in which:—

Figure 1 is a perspective view of the 35 straightening machine showing the housings or supports for the wire engaging elements in the positions they assume before the wire is fed through the machine,

Figure 2 is a similar perspective view 40 showing said housings in the inclined positions they assume when the wire is being fed through the machine,

Figure 3 is a plan view of the main supporting element of the machine and parts 45 carried thereby,

Figure 4 is an enlarged fragmentary plan view of said element showing two only of said housings,

Figure 5 is an end view of the parts 50 shown in Figure 4,

Figure 6 is an enlarged cross-sectional view of the main supporting element, showing in detail one of the housings for the wire engaging elements, and the supporting yokes therefor, and

Figure 7 is a vertical sectional view of the housing and wire engaging element shown in Figure 6.

In the particular embodiment of the invention shown in the accompanying drawings the improved wire straightening machine comprises a main supporting element 1, which comprises end heads 2 and 3 which are connected by means of longitudinally extending parallel and spaced apart side 60 members or webs 4 forming between them a central space 5 within which are located the housings or supports for the wire engaging elements hereinafter referred to. Formed integrally with the end heads 2 and 3 and extending longitudinally therefrom, are the shaft portions 6 and 7 which are respectively rotatably supported in bearings 8 and 9 (Figs. 1 and 2) which may be 65 of any suitable or desired construction. The main supporting element 1 may be rotated at a suitable speed by any convenient means which is not specifically shown in the present application, as it forms no part 70 of the present invention. It may be stated, however, that in the particular embodiment shown the supporting member is adapted to be rotated by means of a spiral gear secured on the shaft portion 7 within the bearing 9 and meshing with another spiral 75 gear on a shaft 10 also rotatably supported in said bearing 9 and which may be driven by any suitable driving means associated therewith, such, for example, as an electric driving motor or a belt drive. Each of the 80 shaft portions 6 and 7 and each end head 2 and 3 is formed with a longitudinally extending bore 11 through which bores the wire to be straightened, and which is indicated at 12 in Figs. 1 and 2, is adapted 85 to be passed, or to be fed by feeding means of any suitable or known kind, such, for example, as feed rolls. The feeding of the wire may be continuous or intermittent and it is immaterial whether the wire is pushed 90 or pulled through the straightening machine. The bearings 8 and 9 may be supported upon any suitable base or foundation structure. It will be seen that the main supporting element is rotated about an axis 95 which is substantially co-incident with the path of the wire through the machine. Arranged within the central space 5 between the side members or webs 4 of the main supporting element, and located at 100

- spaced points along the path of the wire 12, are a plurality of housings 13 which are shown in detail in Figs. 6 and 7. Each housing is made up of two half-housings 14, 15 as shown particularly in Fig. 7, which are secured together by means of screws 16 as shown in Fig. 6, or by means of bolts 17 as indicated in Figs. 1 and 2. Concentrically arranged within each housing 13 is 10 an annular wire engaging element or ring 18 which may be formed of tool steel suitably hardened and ground and provided with a rounded inner periphery as indicated at 19. The annular wire engaging element 18 is held between clamping rings 20 which are secured together by means of screws 21 which pass through apertures in the wire engaging element. These clamping rings are provided with outwardly extending 20 flanges 22 between which, and surrounding the clamping rings and wire engaging element, is secured an inner race member 23 of an anti-friction bearing 24. The half-housings 14 and 15 are also provided with 25 inwardly extending flanges 25 between which is secured the outer race member 26 of the anti-friction bearing, and between the race members 23 and 26 are arranged suitably anti-friction elements such as balls 27. 30 If desired, suitable grease retaining and guard rings 28 and 29 may be secured in place between the flanges 22 and 25. It will be seen that with this construction the wire engaging element 18 while carried or supported by the housing 13, and held in the plane of the housing, is by reason of the anti-friction bearing 24 capable of complete freedom of rotative movement relatively to 35 said housing.
- 40 Each half-housing 14 and 15 is provided at opposite sides thereof with a laterally extending semi-cylindrical portion 28 and over each pair of these semi-cylindrical portions is forced a sleeve 29 so as to form the opposite laterally projecting trunnions or pivots 30 and 31. These trunnions or pivots 30 and 31 are supported within bearings 32 and 33 formed in or carried by yoke members 34 and 35, which extend transversely 45 across the central space 5 of the main supporting element 1 above and below said space, and are provided at their opposite ends with flanges 36 which rest upon the side members or webs 4 of said main supporting element and are secured thereto by 50 means of screws 37 as shown in Fig. 3, or by means of bolts 38, as shown in the remaining figures, passing through said webs.
- 55 The bearing 33 of the yoke 35 in which the trunnion 31 is arranged, is formed by the interior surface or bore of a sleeve 39 which is exteriorly screw-threaded and is arranged within a correspondingly threaded aperture 40 formed in the yoke 35. The sleeve 39 at its inner end bears against the adjacent side of the housing 13 and at its outer end it is formed with a hexagonal or other shaped head 41 by means of which it may be turned. The sleeve 39 is held in place relatively to the trunnion 31 by means of a disk 42 and a screw 43 engaging with a threaded aperture formed between the semi-cylindrical portions 28 of the trunnion. The yoke 35 is slit for a distance outwardly 70 from the aperture 40 therein, as indicated at 44 particularly in Figs. 3 and 4, and the slit parts of the yoke so formed are adapted to be drawn together to grip the threaded sleeve 39 by means of a bolt 45 passing through said slit portions of the yoke. 75
- It will be understood from the construction described that the housing 13 by reason of the trunnions 30 and 31 is capable of swinging movement about the axis of the trunnions which axis is perpendicular to the axis of rotation of the main supporting element 1, and that the housing being supported in yokes 34 and 35 secured to the side members or webs 4 of the main supporting element, also rotates with said element about its axis of rotation. It will also be noted, particularly from Fig. 6 in which the axis of rotation of the main supporting element is indicated at A, that the axis B about which the housing 13 swings is offset from the axis of rotation A, and furthermore that the axis or center C of the wire engaging element or ring 18 is also offset from the axis of rotation A, so as to bring the inner periphery 19 of said wire engaging element relatively close to the axis A at one part thereof. The offsetting of the axis or center C of the wire engaging element is obtained, in the particular construction described, due to the fact that the inner surface of the yoke member 35, against which surface the adjacent side of the housing 13 may abut, as shown in Fig. 6, is closer to the axis of rotation A than is the inner surface of the opposed yoke member 34, and it will be seen 90 that by loosening the bolt 45 and rotating the threaded sleeve 39 within the threaded aperture 40 of the yoke member 35, the position of the housing with reference to the yoke member may be varied and thereby the extent of the offsetting of the axis or center C of the wire engaging element with reference to the axis of rotation A correspondingly varied. This adjustment varies the distance from the axis of rotation A of the adjacent part of the inner periphery 19 of the wire engaging element. The threaded sleeve 39 may be clamped in the adjusted position by tightening the bolt 45. 95
- 100 It will be noted from Figs. 1 to 5 that the arrangement of the yoke members 34 and 35 for each housing is the reverse of the arrangement of the yoke members of the next adjacent housing at either side thereof. That is to say, referring particu- 105
- 110 115 120 125 130

larly to Figs. 1 and 2, the housing at the extreme left of the figure has its yoke member 35 above the webs 4 and its yoke member 34 below said webs, while the next housing has its yoke member 35 below the webs 4 and its yoke member 34 above said webs. The third and fifth housings have their yoke members arranged the same as the first housing and the fourth housing has its yoke members arranged the same as the second housing. The result of this alternately reversed arrangement of the yoke members of the alternate housings, is that the axes or centers of the wire engaging elements are alternately offset to opposite sides of the axis of rotation A about which the housings rotate. Thus in Fig. 6, C indicates the axes or centers of the wire engaging elements of the second and fourth housings from the left in Fig. 1, these axes being offset above the axis of rotation A, while C' indicates the axes or centers of the wire engaging elements of the first, third and fifth housings, these axes being offset below the axis of rotation A.

It has been stated that the axis B about which the housing 13 may swing or turn is offset with respect to the axis of rotation A, and the arrangement of the yokes 34 and 35 of alternate housings is also reversed in this respect, so that the axes about which alternate housings may swing or turn are offset to opposite sides of the axis of rotation. This is shown more particularly in Figs. 4 and 5, but it is indicated also in Fig. 6 in which B indicates the axes about which the second and fourth housings from the left in Fig. 1 may swing, while B' indicates the axes about which the first, third and fifth housings may swing. It will also be noted from Fig. 6 that with this arrangement the axes or centers C and C' are also offset somewhat with respect to a plane passing through the axis of rotation A and parallel with the axes B and B'. Only one housing and the yokes 34 and 35 thereof are shown in Fig. 6 but the arrangement of the alternate housings and yokes thereof is indicated clearly in Fig. 5.

The position which the housings 13 normally assume when the wire is not being fed through the machine is indicated in Fig. 1, in which the housings lie in substantially parallel planes transverse to the axis of rotation, and if the wire 12 is inserted in the machine with the housings in this position the wire will engage with the wire engaging elements at staggered points alternately at opposite sides of the axis of rotation, such engagement, of course, occurring at those parts of the inner peripheries 19 of the wire engaging elements which are brought closest to the axis of rotation due to the offsetting of the centers of the wire engaging elements. This will be

clear from Fig. 6 when it is remembered that the axis or path of movement of the wire is substantially co-incident with the axis of rotation A, the approximate position of the wire being indicated by the dotted lines. It will also be noted that with the parts in the positions indicated in Fig. 6 the points of engagement are alternately above and below the axis of rotation, and offset with respect to the axes B and B' about which the housings may swing or turn, and are intermediate these axes.

If now the wire is advanced through the machine it will by engagement with the inner peripheries of the wire engaging elements turn or swing the housings 13 about their axes B and B' so that these housings lie in planes which intersect the axis of rotation, or the path of the wire, at an inclination, as indicated in Fig. 2 and as shown approximately by the dotted line positions of the housings in Fig. 4. As the points of engagement of the wire with the wire engaging elements are intermediate the axes B and B' and thus in effect offset in different directions from these axes, the housings will be turned to lie in planes inclined alternately in opposite directions with respect to the axis of rotation, as clearly indicated in Figs. 2 and 4.

When the main supporting element 1 is rotated about its axis of rotation, the housings 13 and with them the wire engaging elements will be bodily revolved about the axis of rotation, which is co-incident with the path of the wire, and as the wire engaging elements are capable of complete freedom of rotation relatively to the housings 13, these elements will in effect roll upon the exterior surface of the wire, the successive points of engagement following a path of substantially uniform radius about the axis of rotation. The effect of the engagement of the several rapidly revolving and independently rotatable elements with the wire is to remove therefrom all kinks, bends and undulations therein, with the result that the wire as it emerges from the machine is perfectly straight and true.

For some applications of the straightening machine the wire engaging elements may be located in the angular position such as shown in Fig. 2, in which case these elements will serve the double purpose of straightening and feeding the wire at the same time, the speed of feeding being dependent upon the degree of angularity, the circumference of the wire and the speed of revolution of the supporting element 1.

It is, of course, to be understood that the invention is not restricted to the particular details of construction herein described and illustrated as these may be varied in many ways without departing from the essential

features of the invention as outlined in the claims appended hereto.

I claim:

1. A machine for straightening wire, which comprises a plurality of wire engaging members surrounding the path of the wire spaced apart along said path and rotatable about a common axis substantially co-incident with said path, each of said member having an opening through which the wire passes of materially greater diameter than the diameter of the wire, and each occupying a position such that a point on the peripheral wall of said opening is located at a fixed distance from the axis of rotation substantially equal to the radius of the wire, and means for holding the wire engaging members in said positions and for rotating the same about said axis.
2. A machine for straightening wire, which comprises a plurality of wire engaging members surrounding the path of the wire, spaced apart along said path and rotatable about a common axis substantially co-incident with said path, each of said members having an opening through which the wire passes of materially greater diameter than the diameter of the wire, and each occupying a position such that a point on the peripheral wall of said opening is located at a fixed distance from the axis of rotation substantially equal to the radius of the wire, and means for holding the wire engaging members in said positions and for rotating the same about said axis, each wire engaging member having freedom of rotative movement about its axis relatively to said holding means.
3. A machine for straightening wire, which comprises a plurality of elements spaced apart along the path of the wire and rotatable about a common axis substantially co-incident with said path, means for supporting said elements and rotating the same about said axis, and a plurality of wire engaging members each having an opening through which the wire passes of materially greater diameter than the diameter of the wire, and each held by one of said elements in a position such that a point on the peripheral wall of said opening is located at a fixed distance from the axis of rotation substantially equal to the radius of the wire.
4. A machine for straightening wire, which comprises a plurality of elements spaced apart along the path of the wire and rotatable about a common axis substantially co-incident with said path, means for supporting said elements and rotating the same about said axis, and a plurality of wire engaging members each having an opening through which the wire passes of materially greater diameter than the diameter of the wire, and each held by one of said elements in a position such that a point on the peripheral wall of said opening is located at a fixed distance from the axis of rotation substantially equal to the radius of the wire, each wire engaging member being mounted in the corresponding element so as to be capable of rotative movement about the axis of the opening therein.
5. A machine for straightening wire, comprising a plurality of elements spaced apart along the path of the wire and rotatable about a common axis substantially co-incident with said path, and each swingable about an axis perpendicular to the axis of rotation, and a plurality of annular wire engaging elements each carried by one of said rotatable elements and having freedom of rotative movement relatively thereto.
6. A machine for straightening wire, comprising a plurality of elements spaced apart along the path of the wire and rotatable about a common axis substantially co-incident with said path, and each swingable about an axis perpendicular to and offset from the axis of rotation, and a plurality of annular wire engaging elements each carried by one of said rotatable elements and having freedom of rotative movement relatively thereto.
7. A machine for straightening wire, comprising a plurality of elements spaced apart along the path of the wire and rotatable about a common axis substantially co-incident with said path and also swingable about parallel axes perpendicular to and offset to opposite sides of the axis of rotation, and a plurality of annular wire engaging elements each carried by one of said rotatable elements and having freedom of rotative movement relatively thereto.
8. A machine for straightening wire, comprising a plurality of elements spaced apart along the path of the wire and rotatable about a common axis substantially co-incident with said path and each swingable about an axis perpendicular to the axis of rotation, and a plurality of annular wire engaging elements each carried by one of said rotatable elements with its axis offset relatively to the axis of rotation and having freedom of rotative movement relatively to said rotatable element.
9. A machine for straightening wire, comprising a plurality of elements spaced apart along the path of the wire and rotatable about a common axis substantially co-incident with said path and also swingable about parallel axes perpendicular to and offset to opposite sides of the axis of rotation, and a plurality of annular wire engaging elements each carried by one of said rotatable elements and having freedom of rotative movement relatively thereto, the alternate wire engaging elements having a

common axis offset to one side of the axis of rotation, and the intermediate wire engaging elements having a common axis offset to the opposite side of said axis of rotation.

- 5 10. A machine for straightening wire, comprising supporting means rotatable about an axis substantially co-incident with the path of the wire, and a plurality of wire engaging elements in the form of relatively thin flat rings through which the wire passes, each having an internal diameter materially greater than that of the wire, said elements being carried by said supporting means with their axes offset definite fixed 15 equal distances from the axis of rotation and spaced apart along said path.

- 10 15. A machine for straightening wire, comprising supporting means rotatable about an axis substantially co-incident with the path of the wire, and a plurality of wire engaging elements in the form of relatively thin flat rings through which the wire passes, each having an internal diameter materially greater than that of the wire, said 20 elements being carried by said supporting means with their axes offset definite fixed equal distances in different directions relatively to the axis of rotation and spaced apart along said path, each element being 25 mounted so as to have freedom of rotative movement relatively to said supporting means.

- 20 25. 12. A machine for straightening wire, comprising supporting means rotatable about an axis substantially co-incident with the path of the wire, and a plurality of ring shaped wire engaging elements through which the wire passes carried by said supporting means in eccentric relation to said axis and spaced apart along said path, each element being mounted to turn freely about an axis perpendicular to the axis of rotation and to have freedom of rotative movement relatively to said supporting means.

- 30 35. 13. A machine for straightening wire, comprising supporting means rotatable about an axis substantially co-incident with the path of the wire, and a plurality of annular wire engaging elements carried by 40 said supporting means and spaced apart along said path, each element being mounted to turn about an axis perpendicular to and offset from the axis of rotation and to have freedom of rotative movement relatively to said supporting means.

- 45 50. 14. A machine for straightening wire, comprising supporting means rotatable about an axis substantially co-incident with the path of the wire, and a plurality of 55 annular wire engaging elements carried by said supporting means and spaced apart along said path, said elements being mounted to turn about parallel axes perpendicular to and alternately offset to

opposite sides of the axis of rotation, and to have freedom of rotative movement relatively to said supporting means.

55 60. 15. A machine for straightening wire, comprising supporting means rotatable about an axis substantially co-incident with the path of the wire, and a plurality of annular wire engaging elements carried by 65 said supporting means and spaced apart along said path, the alternate elements having their axes offset to one side of the axis of rotation, and the intermediate elements having their axes offset to the opposite side of said axis, said elements being mounted to turn about parallel axes perpendicular to and alternately offset to opposite sides of 70 the axis of rotation, and to have freedom of rotative movement relatively to said supporting means.

75 80. 16. A machine for straightening wire, comprising a plurality of independently rotatable, wire engaging elements of materially greater internal diameter than the wire arranged in spaced apart relation and all of them having their centers offset equidistantly in different radial directions with respect to 85 the path of the wire sufficiently to bring the interior surfaces of said elements into engagement with the wire to be straightened, and means for revolving all of said elements bodily about an axis substantially co-incident 90 with the path of the wire, to cause said elements to have rolling engagement with the surface of said wire.

95 100. 17. A machine for straightening wire, comprising a plurality of independently rotatable, ring shaped wire engaging elements through which the wire passes arranged in spaced apart relation along the path of the wire in planes intersecting said path at an inclination, and means for revolving said 105 elements bodily about an axis substantially co-incident with the path of the wire.

110 115. 18. A machine for straightening wire, comprising a plurality of independently rotatable, wire engaging elements in the form of relatively thin flat rings of greater internal diameter than the wire arranged in spaced apart relation and having their centers offset equidistantly in different radial directions with respect to the path of the wire to bring points on their interior surfaces into positions to engage the wire, said elements being arranged in planes intersecting said path at an inclination, and means for revolving said elements bodily 120 about an axis substantially co-incident with the path of the wire.

125 130. 19. A machine for straightening wire, comprising a plurality of annular wire engaging elements arranged in spaced apart relation along the path of the wire, each element being mounted for independent rotation and for movement about an axis per-

pendicular to and offset from said path, and means for revolving said elements bodily about an axis substantially co-incident with said path.

5 20. A machine for straightening wire, comprising a plurality of annular wire engaging elements arranged in spaced apart relation along the path of the wire, said elements being mounted for independent rotation and for movement about axes perpendicular to and alternately offset to opposite sides of said path, and means for revolving said elements bodily about an axis substantially co-incident with said path.

10 21. A machine for straightening wire, comprising a plurality of annual wire engaging elements arranged in spaced apart relation along the path of the wire, said elements being mounted for independent rotation and for movement about axes perpendicular to and alternately offset to opposite sides of said path and having their centers offset equidistantly in different radial directions with respect to said path, 25 and means for revolving said elements bodily about an axis substantially co-incident with said path.

20 22. A machine for straightening wire, comprising a plurality of supporting elements arranged in spaced apart relation along the path of the wire and mounted to turn about axes perpendicular to and offset from said path, a plurality of annular wire engaging elements carried by said supporting elements and each freely rotatable with respect to its supporting element, and means for revolving said elements bodily about an axis substantially co-incident with the path of the wire.

25 23. A machine for straightening wire, comprising a main supporting means, a plurality of supporting elements arranged in spaced apart relation along the path of the wire and each having oppositely projecting trunnions mounted in said supporting means so that said elements may turn about axes perpendicular to said path, a plurality of ring shaped wire engaging elements of larger internal diameter than the wire carried by said supporting elements with their centers offset equidistantly in different radial directions with respect to said path and each freely rotatable with respect to its supporting element, and means for 50 revolving said supporting means bodily about an axis substantially co-incident with the path of the wire.

55 24. A machine for straightening wire, comprising a main supporting member rotatable about an axis substantially co-incident with the path of the wire, a plurality of supporting elements carried by said supporting member and arranged in spaced apart relation along the path of the wire,

60 and a plurality of ring shaped wire engaging elements of greater internal diameter than the wire carried by said supporting elements and positioned thereby with the axes of all of them offset equal distances in different directions from said axis of rotation and each freely rotatable with respect to its supporting element.

65 25. A machine for straightening wire, comprising a main supporting member rotatable about an axis substantially co-incident with the path of the wire and having parallel side members at opposite sides of said path, upper and lower pairs of brackets extending across between said side members, a plurality of supporting elements arranged 70 in spaced apart relation along the path of the wire, each of said supporting elements being pivotally carried by an upper and lower pair of said brackets for movement about axes perpendicular to said path, and a plurality of annular wire engaging elements carried by said supporting elements and each freely rotatable with respect to its supporting element.

75 26. A machine for straightening wire, comprising a main supporting member rotatable about an axis substantially co-incident with the path of the wire, a plurality of supporting elements arranged in spaced apart relation along the path of the wire, 80 said supporting elements being pivotally carried by said main supporting member for movement about axes perpendicular to and alternately offset to opposite sides of said path, and a plurality of annular wire engaging elements carried by said supporting elements and each freely rotatable with respect to its supporting element.

85 27. A machine for straightening wire, comprising a plurality of ring shaped wire 90 engaging elements of greater internal diameter than the wire arranged in spaced apart relation along the path of the wire, and in such eccentric relation to said path that a point on the interior surface of each element is positioned a distance from said axis substantially equal to the radius of the wire, means for revolving said elements bodily about an axis substantially co-incident with the path of the wire, and an anti-friction-bearing mounting for each element rendering the same freely rotatable.

95 28. A machine for straightening wire, comprising a plurality of supporting elements arranged in spaced relation along the path of the wire and each surrounding said path, a plurality of ring shaped wire engaging elements of greater internal diameter than the wire carried by said supporting elements, with the axes of all of them spaced equal distances in different directions from the said path, an anti-friction bearing interposed between each wire engag-

ing element and its supporting element, and means for revolving said elements bodily about an axis substantially co-incident with the path of the wire.

- 5 29. A machine for straightening wire, comprising a plurality of independently rotatable, ring shaped, wire engaging elements of greater internal diameter than the wire arranged in spaced apart relation and 10 having their centers offset equidistantly in different radial directions with respect to the path of the wire, means operative to move said wire engaging elements to vary the distance of the centers thereof from said 15 path, and means for revolving said elements bodily about an axis substantially co-incident with the path of the wire.
30. A machine for straightening wire, comprising a plurality of supporting elements arranged in spaced apart relation 20 along the path of the wire and each surrounding said path, a plurality of ring shaped wire engaging elements of greater internal diameter than the wire carried by 25 said supporting elements with their centers offset equidistantly in different radial directions with respect to said path and each freely rotatable with respect to its supporting element, means operative to move said 30 supporting elements to vary the distance of the centers of the wire engaging elements from said path, and means for revolving said elements bodily about an axis substantially co-incident with the path of the wire.
- 35 31. A machine for straightening wire, comprising a plurality of supporting elements arranged in spaced apart relation along the path of the wire and mounted to 35 turn about axes perpendicular to said path, 40 means operative to adjust said supporting elements along said axes, a plurality of ring shaped wire engaging elements of greater internal diameter than the wire carried by 45 said supporting elements and each freely rotatable with respect to its supporting element, and means for revolving said elements bodily about an axis substantially coincident with the path of the wire.

32. A machine for straightening wire, comprising an element rotatable about an axis substantially co-incident with the path of the wire, a plurality of relatively thin flat disc-like wire engaging elements carried by said rotatable element and freely rotatable relatively thereto, and each adapted to have substantially point contact with the wire, and means for adjusting said elements toward or from said path.

33. A machine for straightening wire, comprising a plurality of supporting elements arranged in spaced apart relation along the path of the wire and mounted to turn about axes perpendicular to said path, a plurality of relatively thin flat disc-like wire engaging elements carried by said supporting elements, and each adapted to have substantially point contact with the wire, and means for bodily revolving said supporting elements about an axis substantially co-incident with said path.

34. A machine for straightening wire, comprising a plurality of supporting elements arranged in spaced apart relation along the path of the wire and mounted to turn about axes perpendicular to and offset from said path, a plurality of wire engaging elements carried by said supporting elements, and means for bodily revolving said supporting elements about an axis substantially co-incident with said path.

35. A machine for straightening wire, comprising a plurality of supporting elements arranged in spaced apart relation along the path of the wire and mounted to turn about axes perpendicular to and alternately offset to opposite sides of said path, a plurality of wire engaging elements carried by said supporting elements, and means for bodily revolving said supporting elements about an axis substantially co-incident with said path.

In testimony whereof I affix my signature.

WALTER F. SCHULZ.
